Attorney/s:

UNITED STATES PATENT OFFICE.

WILLIAM C. BANFILL, OF IPSWICH, MASSACHUSETTS.

AXLE-LUBRICATOR.

SPECIFICATION forming part of Letters Patent No. 357,565, dated February 15, 1897.

Application filed December 24, 1886. Serial No. 222,488. (No model.)

To all whom it may concern:

Be it known that I, WILLIAM C. BANFILL, a citizen of the United States of America, residing at Ipswich, in the county of Essex and 5 State of Massachusetts, have invented certain new and useful Improvements in Axle-Lubricators, of which the following is a specification, reference being had therein to the accompanying drawings.

10 This invention pertains to certain new and useful improvements in axle-lubricators; and it consists in the detailed construction, combination, and arrangement of the parts, substantially as hereinafter fully set forth, and particularly pointed out in the claims.

In the accompanying drawings, Figure 1 is a vertical sectional view of my invention, and Fig. 2 is a side elevation thereof.

15 In carrying out my invention I form the outer or bearing end of the vehicle-axle A with a central passage or aperture, a, which extends from the extreme outer end of the axle to a point a short distance beyond the flange against which the inner side portion of 20 the wheel-hub is designed to bear. A small vertical passage, a', opens into this central passage or aperture at its rear end, said vertical passage having the lower screw-threaded end of a small lubricant or oil cup, a'', screwed 25 therein, the object of which will soon appear. Two corresponding vertical passages, b b', are formed in the lower portion of the axle, the same being formed near the inner and outer ends, respectively, of the central passage or 30 aperture, into which they open at their upper ends.

35 On the outer surface of the axle are formed two spiral grooves, B B', extending at their lower ends from the ends of the two vertical 40 passages b b' and meeting at a point equidistant the length of the bearing end of the axle, where they open into a third vertical passage, b'', formed in the upper wall of the axle and extending into the central passage or aperture. 45 These spiral grooves are made to run in the direction in which the wheel revolves when the vehicle is in motion. From this it will be

seen that oil being first supplied in the lubricant or oil cup, the same will pass through the small passage a' into the central passage 50 or aperture, a, and out through the vertical passage b. The movement of the wheel being in the direction of the spiral grooves will carry the oil up through the spiral groove B, and upon reaching the third vertical passage, b'', it 55 will pass down through the same into the central passage or aperture, and out through the second vertical passage, b', from whence it will be carried in the spiral groove B' up to the said upper passage, b'', and thus continuously 60 repeating the operation. It will be observed that the bearing end of the axle will thus be kept thoroughly oiled or lubricated, and the oil will be reused continuously until entirely exhausted.

65 Having thus fully described my invention, what I claim, and desire to secure by Letters Patent, is—

1. The herein-described axle-lubricator, consisting of the bearing end having a central passage or aperture, the vertical passages, and the spiral grooves extending from two of said passages and opening into a third vertical passage, substantially as shown and described.

2. The combination, with the axle having 75 the central passage or aperture and the lubricant or oil cup, of the spiral grooves connected at their lower ends with said central passage by vertical passages and opening at their upper ends into a third passage, substantially as 80 shown and described.

3. The combination, with the axle having a central passage or aperture and the vertical passages, of the spiral grooves formed on the outer side of said axle, and connected at their 85 ends with said central passage, substantially as shown, and for the purpose described.

In testimony whereof I affix my signature in presence of two witnesses.

WILLIAM C. BANFILL.
